United States Patent

Des. 240,969
Patented Aug. 10, 1976

240,969

PORABLE HAIR DRYER

Dale E. Fahnstrom, Riverside, and Robert D. Peterson,
Chicago, Ill., assignors to The Gillette Company, Bos-
ton, Mass.

Filed Sept. 3, 1974, Ser. No. 502,353

Term of patent 14 years

Int. Cl. D28—03

U.S. Cl. D86—10 F

Fig. 4

Fig. 5

Fig. 6

FIG. 1 is a perspective view of a portable hair dryer showing our new design;

FIG. 2 is a right end elevational view;

FIG. 3 is a left end elevational view;

FIG. 4 is a top plan view;

FIG. 5 is a rear elevational view; and

FIG. 6 is a bottom plan view.

The cord is depicted only partially for convenience of illustration.

We claim:

The ornamental design for a portable hair dryer, as shown and described.
